RICHARD F. CRITTENDEN, OF SAN FRANCISCO, CALIFORNIA, ASSIGNOR OF ONE-HALF
TO ALEXANDER M. THYES, OF SAN FRANCISCO, CALIFORNIA.

MOISTENING DEVICE.

1,197,449.

Specification of Letters Patent. Patented Sept. 5, 1916.

Application filed February 25, 1914. Serial No. 821,017.

To all whom it may concern:

Be it known that I, RICHARD F. CRITTENDEN, a citizen of the United States, residing in the city and county of San Francisco, State of California; and whose post-office address is 525 Market street, have invented certain new and useful Improvements in Moistening Devices; and I do hereby declare the following to be a full, clear, and exact description of said invention, such as will enable others skilled in the art to which it most nearly appertains to make, use, and practise the same.

Among the many objects of the invention are, to provide a device of this character, so designed that it can be constructed wholly of metal; to eliminate all absorbents, such as sponges, wicks and the like from the moistener; to provide an air locked reservoir for the supply of moisture, automatically delivered, without the interposition of valves or moving parts.

The invention possesses other advantageous features that with the foregoing will be set forth at length in the following description, wherein I shall outline in full that form of the invention selected for illustration in the drawings accompanying and forming a part of the present specification. The novelty of the invention will be included in the claims following said specification. From this it is apparent that I do not restrict myself to the showing made by said drawings and specification; as I may adopt many variations within the spirit of this invention, as exposed in said claims.

In the drawings: Figure 1—is a longitudinal cross section of a moistening device constructed in accordance with this invention. Fig. 2—is a plan view from above of the same. Fig. 3—is a similar view taken on the line III—III.

Construction.—In detail the construction as illustrated consists of the tubular reservoir 1, with the closed bottom 2, and the top 3, having the opening 4, therethrough. The reservoir thus constructed is air locked, that is to say, water confined therein will not spill or flow out except, by capillary or similar force, or by a side shake or jar that will break the air lock or vacuum created behind the body of water when the reservoir is inverted. The top 3 is spaced down from the upper edge of the tube, forming the sides of the reservoir, about one-quarter of an inch,

in practice this distance proving about correct. This space 5 will vary somewhat according to the proportions of the device. The open end of the cap 6 telescopes over the reservoir 1, until the top 7, abuts the upper edge of the tube. The top of the cap is provided with a multiplicity of small openings, or perforations 8, better to distribute the water discharged from the reservoir. For ease in manufacturing it is preferable to perforate this cap with a multiplicity of round holes. This is not arbitrary however, as narrow slits or fancifully shaped perforations will serve equally well, so long as they are small enough to prevent an excess of water gushing through the gap. The top 3 acts as a buffer plate to break the force of the water or liquid within the receptacle or moistener when the latter is inverted for use, and thereby prevents the contents of the moistener squirting out through the perforations or openings 8' each time the device is inverted.

Operation.—This device is operated as follows: The cap is removed and the reservoir submerged or otherwise wholly or partially filled with water, so that the water does not rise above the top 3, the cap is then placed in position, being forced down until its top abuts the edge of the tube as described. The gummed surface to be moistened is laid upon a smooth surface, with the gummed side up. The moistening device is inverted and passed across the top of the gummed surface, with sufficient pressure to create a slight vacuum in each tiny perforation in the cap, sufficient to withdraw the water held therein. The water thus drawn through the perforated cap is replaced by water flowing through the opening 4, due to the violent agitation of the water incidental to the operation of the device, in being passed across the gummed surface as described. The water thus applied to the gummed surface is distributed by the drag of the cap over the surface. The smallness of the openings in the cap and their close contact with the gummed surface prevents the entrance of a sufficient volume of air to release an excess of water when the airlock of the reservoir is broken; this smallness of these openings also prevents the discharge of any excess quantity of water from the space 5.

Among the advantages of this invention

might be mentioned its sanitary construction wholly of metal, hard rubber, celluloid or other suitable materials having no chemical reaction with water. The cap having no affinity for the gummed surface, no gum is removed therefrom. The whole device being compact and self contained is convenient in operation and may be carried in the pocket. There is no moist surface such as 10 capillary moisteners have, so it is not a source of damage if exposed upon desks, as the water will not flow therefrom if the moistener is accidentally upset or papers laid upon it.

15. Having thus described this invention, what is claimed and desired to secure by Letters Patent is:

Copies of this patent may be obtained for five cents each, by addressing the "Commissioner of Patents, Washington, D. C."

1: A moistener having a reservoir closed at one end, a cap on the other end of the reservoir having a flat, perforated discharge 20 wall, and an apertured buffer plate fixed in said reservoir in spaced relation to the cap.

2. A moistener including an air locked reservoir having a perforated top spaced from the edge thereof; and a cap engaging 25 said reservoir, and having a perforated plane top.

In testimony whereof, I have hereunto set my hand this 27th day of January, 1914.

RICHARD F. CRITTENDEN.
